CIGARETTE BOX

Irving Silverman, New York, N. Y., assignor to Rogers Imports Inc., New York, N. Y., a corporation of New York

Application May 19, 1947, Serial No. 139,132

Term of patent 3½ years

(Cl. D85—2)

To all whom it may concern:

Be it known that I, Irving Silverman, a citizen of the United States, residing at New York, in the county of New York and State of New York, have invented a new, original, and ornamental Design for a Cigarette Box, of which the following is a specification, reference being had to the accompanying drawings, forming part thereof.

Fig. 2 is a side elevational view thereof;

Fig. 3 is an end elevational view thereof; and

Fig. 4 is a fragmentary vertical sectional view taken from the left of Fig. 2.

I claim:

The ornamental design for a cigarette box, as shown.

IRVING SILVERMAN.
